UNITED STATES PATENT OFFICE.

WILLIAM H. KIENKER, OF RICHMOND, INDIANA.

ELECTRICALLY-OPERABLE OPEN-AT-WILL ELEVATOR-GATE MECHANISM.

1,037,637.

Specification of Letters Patent.

Patented Sept. 3, 1912.

Application filed August 2, 1911. Serial No. 641,888.

To all whom it may concern:

Be it known that I, WILLIAM H. KIENKER, a citizen of the United States, and a resident of the city of Richmond, in the county of Wayne and State of Indiana, have produced certain new and useful Improvements in Electrically-Operable Open-at-Will Elevator-Gate Mechanisms, of which the following is a full, clear, and comprehensive specification and exposition, being such as will enable others to make and use the same with absolute exactitude.

The object of my present invention, broadly speaking, is to provide a construction combining a minimum of mechanical elements into an electrically operable, open at will, elevator-gate mechanism, which will be strong and durable in construction, simple to effectuate, positive in action, and which can be manufactured and sold at a comparatively low price.

A more specific object is to provide a mechanical construction which will contain only the indispensable requisites for an electrically operable, open at will, elevator gate mechanism whereby the gates which guard the various hatchways of the elevator-shaft will remain closed, regardless of the number of times the elevator-car passes up and down until such time as shall be selected by the operator of the car, and then only providing the floor of the car is approximately even with one of the floors of the building in which the elevator-car is located.

Other objects and particular advantages of my invention will be brought out and made clear in the course of the following specification, and that which is new and useful will be emphasized in the appended claims which terminate this description.

One manner for the construction of my invention, and that which in practice I have found to be the most practical and economically efficient, is shown in the accompanying four sheets of drawings, in which—

Figure 1 shows a perspective view of the arrangement of my invention, as applied to a building having three floors and one intermediate gate to which the operating mechanism is applied, showing the car at the bottom floor. Fig. 2 is a perspective view of my invention as applied to a building having four floors and two intermediate

gates, shewing the car at an intermediate floor. Fig. 3 is an enlarged perspective detail of my invention as shown in Fig. 1, showing certain of the upper mechanism broken away and brought down in order that it may appear in this view with the other mechanisms. Fig. 4 is an enlarged detail view of the locking mechanism. Fig. 5 is detail cross sectional view, as taken on line 5—5 of Fig. 4. Fig. 6 is a detail cross sectional view as taken on line 6—6 of Fig. 4. Fig. 7 is a detail plan view of a portion of one of the latch mechanisms. Fig. 8 is a detail elevation of a portion of one of the latch mechanisms. And Fig. 9 is a detail plan view of one of the switches.

Similar indices denote like parts throughout the several views.

In order that the construction and the operation of my invention may be more fully understood and appreciated I will now take up a detail description thereof in which I will set forth the invention as briefly and as comprehensively as I may.

My present invention is intended to be used in connection with an elevator-car D arranged to travel up-and-down through the shaft which is formed by openings therefor through a plurality of floors, A, B, C, or 2^A, 2^B, 2^C and 2^{C'} for instance, although there may be any number of floors between which the car operates up and down.

It is to be understood that my invention is especially adapted to operate on the intermediate gates which normally close the openings from each floor to the elevator shaft, as shown.

Letters E and F denote the gates which close the openings from the respective floors B and C to the elevator-shaft, as shown in Figs. 1 and 3. As shown in Fig. 2 a fourth floor, 2^{C'} is added; and in Figs. 1 and 3 a gate E' is provided for the first floor. Said gates are mounted to slide up and down in suitable guideways formed in the sides of the openings in any well known manner.

The elevator-car is provided with the usual stationary standards in the center at each side thereof, as the standard d' for instance, which are arranged to guide the car up and down controlled by suitable guides which engage with the track carried by the posts G for instance. The car D is adapted

- to be raised and lowered in any well known manner, as by the cable H by which it may be suspended and lifted. The power for operating the elevator-car is controlled by the small cable I, which operates at the base around pulley J; the upper portion of which is not shown, operates over a similar pulley one of which pulleys may act as the power controller in the usual manner.
- 10 Numerals 1 and 2 denote each a rod which are of the same length and which extend from near the bottom to near the top of the elevator-shaft, the same being carried by and adapted to slide up and down in suitable brackets 3, which latter are secured to the face of the wall K, there being apertures formed through said brackets in which the rods may slide up and down, there also being a space between the side of the car D and the wall K for said rods to be located without interference, as well as other devices which will hereinafter be fully described. The lower ends of the rods 1 and 2 are connected rigidly together by the plate 4, and their upper ends are likewise connected by the plates 5 and 5' which are spaced apart for the purpose hereinafter appearing.
- Secured to the plates 5 and 5', centrally of the rods 1 and 2, is the rack-bar 6. Attached to the upper end of the rack-bar 6 is the rope 7, which extends directly up and then over the pulley 8 and then back to any convenient point and then over a pulley 9, and then down to the counterbalancing weight 10. The specific gravity of weight 10 is such as to normally raise the rods 1 and 2 upward to their highest point of elevation and also the parts thereto attached.
- 40 Letter M denotes an electric motor, of any convenient construction, adapted to revolve the shaft n, on which latter is secured the pulley N, the outer end of the shaft n being supported by the bracket 11 which is secured to the wall K. Also secured to the wall K is the bracket 12 in which is mounted the pulley 13.
- 50 Numeral 14 denotes an endless band or sprocket-chain which operates over pulleys or sprockets N and 13 substantially as shown.
- 55 Numeral 15 denotes a rope, or the like, one end of which is secured in the center of plate 4 (Fig. 3) extending downward, with its lower end secured to the band or chain 14 by means of the finger 16, as indicated.
- 60 From the above it is apparent that if the motor be operated in one direction that the band 14 will carry the finger 16 downward, moving the rope 15 downward, and also pulling the rods 1 and 2 downward and thereby raising the weight 10. After the rods 1 and 2 have been pulled down to their limit it will be seen that if the power be
- cut off from the motor that the weight 10 will return the rods 1 and 2 to their upward position. In order that the last named movement of the chain 17 may be more positive, that is to cause the motor to coast backward, I provide the weight O which is suspended by the cord P, which latter passes over pulley Q and then down and is secured to the opposite side of the band 14 from that of said finger 16. The pulley Q is carried by the bracket R, the latter being secured to the face of the wall K. The weight O causes the motor M to operate idle and reversely when the electric current is cut off.
- 70 A latching device is located at each intermediate floor, all being made identical with each other, and all are carried by and are 75 slidably up and down on the rods 1 and 2, certain details of which are shown in Figs. 7 and 8. All of said latching devices being 80 alike I will describe but one in detail and refer to like parts of the others by similar indices.
- 85 Numeral 20 denotes a yoke extending across and having two apertures in which 90 may neatly slide the two rods 1 and 2. Formed integral with the yoke 20 and extending down centrally therefrom is the stem 21.
- 95 Numeral 22 denotes a plate which has a downwardly extending stem 23 which is pivoted to the lower portion of the stem 21 in such manner that the plate 22 may swing out a limited distance (as in Fig. 1) away from the rods 1 and 2. Two slots e and f 100 are formed in the rear edge of the plate 22 to receive therein the respective rods 1 and 2. The plate 22 normally swings away by gravity so that the said rods will not be in said slots. Mounted in the front edge of 105 plate 22 and extending out centrally thereof is the roller S, which is for the purpose hereinafter set forth. Secured to each of the latching devices is a rope or the like each of which has its other end secured to one of the 110 gates, as for instance rope 24 which extends up to the ceiling above that floor, passing over pulleys 25 and 26 and from the latter directly down to the center of the gate E to which it is attached, as shown in Figs. 1, 2 115 and 3. In like manner each of the other intermediate gates is connected by its rope 24 to a latching device, said ropes extending over like pulleys 25 and 26. In order that the rope 24 may have a straight pull upon 120 its latching device it is evident that an auxiliary pulley 27 may be used.
- 125 Numeral 28 denotes a cam which is secured to the edge of the car and extends above and below the platform thereof and 130 it is adapted to engage the rollers S, as the car moves up and down the shaft, thereby pressing the plate 22 back and causing the rods 1 and 2 to enter the slots e and f, as shown at the right in Fig. 7.

At properly predetermined intervals there are nuts or buttons secured on the rods 1 and 2, as for instance the nuts *c* and *d*, respectively, there being a pair of said nuts for each floor, the same being adapted to engage in sockets *g* and *h* which are formed in the upper face of the plate 22, as shown in Figs. 7 and 8, which are located around the inner portions of the respective slots *e* and *f*. Said engagements of course taking place when the roller *S* is in engagement with the cam 28, at other times the plate 22 is swung out so that the nuts can not engage in the slots thereof. As the cam 28 is carried by the edge of the car it is apparent that the roller *S* must be so located that its contact with the cam will occur only when the floor of the car is even (or nearly so) with one of the intermediate floors. It should be noticed that only one of said rollers *S* can be in engagement with the cam 28 at any one time regardless of the number of floors through which the car is adapted to travel.

Located near the ceiling of the upper floor, in the locality of the rack-bar 6, is the locking mechanism, shown in detail in Figs. 4, 5 and 6, the same being shown as broken away and located below its proper position in Fig. 3 for convenience in drawing. Said locking mechanism operates in connection with the rack-bar 6, and it comprises a pair of brackets 30 and 31 secured to the wall *K*, slightly to the right of the bars 1 and 2. Slidably mounted to operate vertically in the brackets 30 and 31 is the bar 32. Attached to the upper end of bar 32 is the rope 33 which extends up over pulley 34, then across near the ceiling to pulley 35 (which is near the power controlling cable 1) and then down, being secured to cable 1 at the point *x*, whereby the bar 32 will be moved up or down whenever the elevator is started or stopped, which is initiated by the operation of cable 1 a slight distance.

Secured to the bar 32 and spaced apart, and located between brackets 30 and 31, are the two clips 36 and 37. Carried by and connecting the clips 36 and 37 are the two, spaced apart, cam-bars or guides 38 and 39 which are parallel with each other except at their upper and lower ends where they flare apart. The upper third and the lower third of said bars are offset in the same direction (inward) whereby the central third thereof is offset (outward), that is toward the wall *K*, with relation to the other two-thirds, all substantially as shown in Fig. 4.

Secured to the wall *K* is the bracket 40 to which is pivoted the upwardly extending arm 41, which latter carries at its upper end the horizontal shaft 42. Pivoted on shaft 42, in alinement with the rack-bar 6, is the dog 43, the point thereof being adapted to

engage the teeth of the rack-bar 6, the other end of the dog being weighted, as indicated in Fig. 4. Also carried on shaft 42 is the roller 44 whose diameter is slightly less than is the width of the space between the cam-bars 38 and 39, between which it operates as the bar 32 is moved up or down.

From the above it will be apparent that if the right-hand portion of cable 1 be pulled down to start the car down, for instance, that the rope 33 will be pulled in such manner as to raise the bar 32, carrying the cam-bars 38 and 39 upward, which will cause the roller 44 to be located in the lower portion of the space between the cam-bars, thereby moving the dog away from the position where it might contact with the rack-bar 6. It will be apparent that if the left-hand portion of the cable 1 be pulled down, to start the car up, for instance, that the rope 33 will be raised, allowing the bar 32, carrying the cam-bars to move downward, which will cause the roller 44 to be located in the upper portion of the space between the cam-bars, thereby moving the dog away from position to contact with the rack-bar 6, the same as when it was in the lower space. And it is also apparent that when the cable 1 is in normal position, that is the position causing the car to be at rest, that it will cause the roller 44 to be located in the central portion of the space between the cam-bars, thereby causing the dog to be in position to engage or to be engaged by the rack-bar 6, that is when the rack-bar is moved down to the position to be engaged by the dog, as that shown in Fig. 4.

Secured to the wall *K*, opposite each intermediate floor, as the floor *B* for instance, is a pair of contacts 50 and 51; and in alinement therewith but secured on the edge of the car *D* are the two shoes 52 and 53 which are adapted to contact with the respective contacts each time the car is even with that floor.

Secured to the standard *d'*, within reach of the operator of the car, is the push-button 45. Extending from each of the poles of the push-button is a wire, as the wires 54 and 55 shown in Fig. 1. The other ends of said wires are connected to the respective shoes 52 and 53.

Extending in from the source of supply is the service wire 56 which is attached to contact 51, and service wire 57 extends in and is attached to one pole of the meter *M*. Extending from the other pole of the meter is the wire 58 whose other end is attached to the switch shown in detail in Fig. 9. Said switch is attached to the jamb or to the wall *K*, and it consists essentially of the base 59 having a forked pole 60 in which may engage the blade 61, the said blade being normally retained in engagement with the pole 60 by the spring 62, said blade being

hinged at one end. The pole 60 and the blade 61 are insulated from each other when the blade is turned out of the forks of the pole, but when connected they form an electrical connection. Said wire 58 is connected to the pole 60. A wire 63 extends from the spring 62 to the contact 50. Secured to the upper right-hand corner of the gate E, for instance, is a finger 64 which when the gate E is raised to a certain height will push the blade 61 out of contact with the pole 60 against the resiliency of spring 62. In case there are other intermediate floors then a pair of contacts 50 and 51 are provided located opposite to each floor as shown in the above instance, the same being located in position to be impinged by the shoes 52 and 53, and the wire 65 may be extended up to the contact corresponding to contact 51 and located thereabove; while in like manner wire 66 may be extended to a switch for that floor and then to the other contact next above contact 50, and so on regardless of the number of floors in the building.

In Fig. 2 the lower floor shown is denoted by indice 2^a, the next floor above by 2^b, the next by 2^c, and the upper floor by 2^d, the other parts being substantially the same as in the other views.

The operation of my invention may be as follows: The car D is intended to operate up and down in the shaft, passing the various floors but without moving any of the intermediate gates, except at the will of the operator. If the car be located at floor A then if the left-hand portion of the cable I be pulled down the car will start up, and if the car be up and the right-hand portion of cable I be pulled down then the car will start down, all of which is well known and is not part of this invention. Now suppose that the car D in passing up or down should stop at either intermediate floor, as for instance floor B, the gate E of course will still remain closed even after the car stops. But should the operator now press the button 45 then an electric current will be established:—passing through wire 56 to contact 51, then to the shoe 53, then up wire 55, through button 45, then down the wire 54 to the shoe 52, then to contact 50, from the latter it will pass through the wire 63 to the spring 62, then through the blade 61 to the pole 60, then through the wire 58 to the motor M, the other pole of the motor being supplied by the wire 57, thereby completing the circuit. As soon as said circuit is completed the current will start the motor to operate thereby turning the band 14 and pulling the rods 1 and 2 downward endwise. The car being located at floor B it is evident that the cam 28 pressing out on the roller S will cause the slots e and f to stride the respective rods 1 and 2, whereby as the rods are moved down as just stated the nuts

on said rods will engage the plate 22 and thereby carry said plate 22 downward therewith. The rope 24 is secured to the yoke 20, which latter is rigidly connected to said plate 22, by which it is evident that rope 24 at that floor will be pulled with the rods 1 and 2, thereby raising the gate E. It should be noticed at this point that only one gate can be raised at one time, as the car must be opposite a floor in order that the cam 28 may press one of the plates 22 into position to be engaged by the nuts on the rods 1 and 2. Continuing the operation: It is evident that when the gate raises to a point where the finger 64 presses the blade 61 out of contact with the pole 60 that at that time the current will be broken at the latter point and consequently the motor will stop, and therefore the gate will stop and it will be held in its elevated position until the car is started to move up or down, as will hereinafter be described.

During the time certain of the operations just described are taking place another important operation is in process: As the cable I is moved to start the car the rope 33 connected thereto will raise or lower the bar 32, thereby moving the dog 43 out of alignment with the rack 6, but as the cable I is moved to normal position again, to stop the car, at floor B, for instance, the dog will be moved to operative or engaging position, that is midway of the cam-bars 38—39, as in Fig. 4. Now as the bars 1 and 2 are moved downward, as stated, it is evident that the rack 6 will be moved down also, the dog 43 gliding idly over the notches of the rack, but when the circuit is broken, as stated, and the current is cut off from the motor then the weight 10 will tend to draw the rods 1 and 2 back to their first position, that is to their upper limit of movement, but at this time the dog 43 will engage one of the notches of the rack (as in Fig. 4) thereby holding the rack 6 and consequently holding the rods 1 and 2 at their lowered position, thereby retaining the gate E raised, holding it raised as long as the car remains at that floor. However should the operator now desire to move his car to another floor then the first operation will be to move the cable I, to the proper position, to start the car, which of course will move the cam-bars 38—39 up or down which manifestly will pull the dog away from connection with the rack 6, which will allow the weight 10 to pull the rack 6 and the bars 1 and 2 upward which will of course allow the gate E to close by gravity.

From the above it is evident that I provide an open at will elevator gate that is adapted to be opened only when the car is opposite that floor, all gates remaining closed at all times except when the car is opposite a certain floor at which time the

gate at that floor is adapted to be opened but only by a certain means at the will of the operator.

I desire that it be fully understood that various changes may be made in the several details of construction from that herein shown and described without departing from the spirit of my invention or sacrificing any of the advantages thereof.

Having now fully shown and described my invention and the best means for its construction and operation to me known at this time, what I claim and desire to secure by Letters Patent of the United States, is—

1. In an electrically operable open at will elevator-gate mechanism comprising in combination an intermediate gate adapted to close the entrance to an elevator-shaft and a car movable up and down in said shaft, an electric motor, a pair of rods having flexible connection with the motor and extending up beyond the upper floor of the building, means for normally retaining said rods at their highest point, a latching device for each intermediate floor and slidable on said rods, a cam carried by the car for moving the said latches into position to be engaged by said rods, means for flexibly connecting a gate to each latching device whereby the downward movement of the rods will raise the gate opposite to the car, means for holding the gate raised until the car moves from that floor, and means carried by the car for completing the electric circuit to start the motor, all substantially as shown and described and for the purposes set forth.

2. An electrically operable open at will elevator-gate mechanism comprising, in combination with the elevator gates adapted to close the entrances to an elevator shaft and a car adapted to be moved up and down in said shaft, a pair of vertically disposed rods adapted to slide up and down, means for normally retaining said rods at their highest point of elevation, a latching device for each intermediate floor of the building all being slidable up and down on said rods, a cam carried by the car which presses against each of said latches successively as the car passes up and down, an electric motor adapted to operate only when the car is opposite one of the floors of the building, means carried on the car for completing the electric circuit to start the motor, and means for connecting a gate to each of said latches whereby when said rods are lowered the gate opposite the car will be raised, and means for holding the gate open until the car leaves that floor, substantially as set forth.

3. In combination with an elevator-car adapted to operate up and down in a shaft and a gate for each intermediate floor which the car passes, an electrically operable open

at will elevator-gate mechanism comprising the vertically disposed rods extending from near the bottom to near the top of the building and adapted to slide up and down in suitable brackets therefor, the rods being spaced apart and rigidly connected together, a weight having flexible connection with the upper portions of said rods and adapted to normally retain said rods upward to their limits, a latch mechanism for each intermediate floor of the building each of said latch mechanisms being slidably mounted on said rods, each of said latches comprising in combination a yoke, a stem integral with the yoke, a plate having a downwardly extending stem which is pivoted to the first named stem in such manner that the plate may swing out a limited distance, said plate being provided with two slots adapted to stride said rods when the plate is moved in, a roller mounted on said plate, a cam secured on the car and adapted to engage said roller causing said slots to stride said rods, nuts secured on said rods and adapted to engage said plate when the said cam is engaging said roller and the said rods are being moved downward, a motor for moving said rods downward, a flexible connection between each of said latches and its gate whereby when said latch is carried down with said rods the gate will be raised, a system of electric wiring adapted to form a circuit for starting the motor, means located on the car for completing the circuit, means whereby the gate when raised to a certain point will break the circuit, and means for retaining the gate elevated until the car starts to leave that floor, all substantially as set forth.

4. In combination with an elevator-car adapted to operate up and down in a shaft connecting the various floors of a building, an electrically operable open at will elevator-gate mechanism comprising a gate for each intermediate floor of the building, a pair of rods or the like extending from near the upper to near the lower floor of the building, means for normally retaining said rods or the like at their highest point, a latching device located near each intermediate floor and all slidable on said rods, a rope connecting each intermediate gate with one of said latching devices whereby when one of said latching devices is lowered the gate attached thereto will be raised, means carried by the car for placing successively each of said latching devices in position to be engaged by said rods, an electric motor adapted to lower said rods when the electric current is completed, means carried by the car for enabling the operator to complete the electric circuit, means for retaining the gate at its highest point after the electric circuit has been broken, the last named means comprising a rack carried by the upper ends of

the rods, a dog adapted to engage said rack when the elevator is stationary, and means whereby the dog is released from the rack as soon as the elevator is started, and means for breaking the electric circuit upon the gate reaching a certain height, all substantially as shown and described and for the purposes set forth.

In testimony whereof I have hereunto subscribed my name to this specification in the presence of two subscribing witnesses.

WILLIAM H. KIENKER.
